UNITED STATES PATENT OFFICE

2,110,635

REFRIGERATING APPARATUS

Homer E. Rosebrook and Othel I. De Graw,
Greenville, Mich., assignors to Gibson Electric
Refrigerator Corporation, Greenville, Mich., a
corporation of Michigan

Application August 11, 1937, Serial No. 158,601

5 Claims. (Cl. 62—89)

This invention relates to improvements in refrigerating apparatus and more especially to such apparatus of the portable type particularly adapted for domestic use.

5 Among the features of our invention is the combination of a shelf type evaporator adapted to support ice trays with a transverse guide member adjacent the front edge of the shelf and a carriage slidably mounted on the guide member, 10 said carriage being provided with ice tray release mechanism.

Another feature of the invention is the provision of an apron in front of the evaporator shelf, said apron carrying the guide member above mentioned. This apron is preferably made removable to facilitate cleaning and repair. The apron may also support a thermometer.

Another feature of the invention is a vertical removable plate mounted above and in front of the evaporator shelf, in front of the ice trays to conceal the same from view when the door is open, and provide better cooling of the ice trays. Means are provided for swinging this plate upwardly and backwardly to a horizontal position to permit removal of the ice trays from the evaporator shelf and under the plate.

Other features and advantages will appear more fully as we proceed with our specification.

In that form of device embodying the features of our invention shown in the accompanying drawings—Fig. 1 is a view in front elevation of the food compartment of a refrigerator; Fig. 2 is a similar view on an enlarged scale of the upper portion thereof; Fig. 3 is a view taken as indicated by the line 3 of Fig. 2; Fig. 4 is a view taken as indicated by the line 4 of Fig. 2; Fig. 5 is a vertical sectional view taken through the evaporator shelf and the baffles underneath taken on the line 5 of Fig. 6; Fig. 6 is a view taken as indicated by the line 6 of Fig. 5; Fig. 7 is a fragmentary view similar to Fig. 2 taken on an enlarged scale; and Fig. 8 is a view taken as indicated by the line 8 of Fig. 7.

As shown in the drawings, 10 indicates the food compartment of a refrigerator which may be of any conventional type adapted for mechanical cooling. 11, 11 indicate the usual shelves in the compartment for supporting food.

In the refrigerating apparatus here shown we 50 use a shelf type of evaporator which may be, for example, similar to the evaporator shown in Figs. 10, 11, 12, and 13 of Touborg and Rosebrook Patent 2,009,910 issued July 30th, 1935. Since the details of the construction and operation of such an evaporator are fully disclosed in that

patent it is unnecessary that they be repeated here.

The evaporator in general in the form of a flat shelf we have indicated by the reference numeral 12 and the cooling boilers thereunder by the 5 reference numerals 13. We shall use the numeral 12 to indicate the evaporator in general, it being understood that in the practice of this invention we employ any evaporator of the shelf type, that is, any evaporator including a substantially flat imperforate shelf. One of the features of this invention is to make the shelf substantially the same size and shape as a horizontal cross-section of the food chamber 10 and locate 10 said shelf near the top of the chamber so that 15 there will be a small compartment 10a above the shelf for the accommodation of ice trays 14.

In front of the evaporator, across the front of the food compartment, there is provided a removable apron 21, the ends of which are bent 20 at right angles as indicated by 22 and provided with holes 23, 23 to receive the pins 24, 24 in the walls of the food compartment. Springs 25, 25 serve to center the apron on the pins and permit removal of the same from the refrigerator by 25 pressing the same to one side against the compression of one of the springs until the pins on the other side are released.

26 indicates a thermometer carried on the rear side of the apron 21 and visible through a slot 30 27 therein.

Carried between the ends 22, 22 of the apron 21 is a guide member 28 having a carriage 29 slidably mounted thereon, said carriage having rotatably mounted in its upper end the blade 30 member 30 provided with the handle 31. The blade 30 can be rotated in the carriage and also slid backwardly or forwardly. The guide member 28 extends across the front of the refrigerator just back of the apron 21. With this construction, the blade can be moved in front of any ice tray and the flattened end 30a thereon pushed under the curved front edge of the ice tray and the blade rotated to release the ice tray from the shelf 12. (See Fig. 8.)

The upper edges of the apron 21 are bent backwardly to form narrow horizontal flanges 21a and 21b at the upper and lower edges of the apron 21.

32 indicates a vertical removable plate mounted 50 above and in front of the shelf 12 in front of the ice trays. Means are provided for swinging this plate upwardly and backwardly to a horizontal position as shown in broken lines in Fig. 4 to permit removal of the ice trays from the shelf 55

12. When the plate is up, the trays can be slid out from the shelf under the plate. To permit such swinging of the plate, its ends are provided with curved slots 33 and 33a as shown in Fig. 4, 5 engaging the pins 34 and 34a respectively. This construction permits the plate 32 to be rotated substantially 90° so that it can be moved from the position shown in solid lines to that shown in broken lines. The plate 32 is also removable 10 from the box. It is short enough so that it can be pushed to one side against the tension of one of the springs 35 until the pins from the other ends are released from the slots when the plate can be taken out bodily.

15. As another feature of the invention we have also shown the mounting of the thermostat 51a on the back of the apron 21, said thermostat being controlled by the usual knob 51 in co-operation with the dial 50. The wires 52 indicate 20 the usual connections of the thermostat to the rest of the refrigerating apparatus, the details of which need not be shown.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as permissible, in view of the prior art.

What we claim as new, and desire to secure by Letters Patent, is:

1. In refrigerating apparatus, in combination with a shelf type evaporator adapted to support ice trays thereon, a transverse guide member adjacent the front edge of the shelf, a carriage slidably mounted on said guide member, and an ice tray release mechanism carried by said carriage. 5

2. In refrigerating apparatus, in combination with a shelf type evaporator adapted to support ice trays thereon, a vertical plate mounted above 10 and in front of the shelf in front of the ice trays, and means for swinging said plate upwardly and backwardly to a horizontal position to permit removal of ice trays from said shelf and under said plate. 15

3. Apparatus as claimed in claim 2 in which the plate is bodily removable from the refrigerating apparatus.

4. Refrigerating apparatus, including: a shelf type evaporator; a transverse apron adjacent the front edge of the shelf, the ends of said apron being bent backwardly at right angles; a transverse guide member carried by said backwardly bent ends of the apron, a carriage slidably mounted on said guide member; and ice tray 25 release mechanism carried by said carriage. 20

5. Refrigerating apparatus, including: a shelf type evaporator; a transverse apron adjacent the front edge of the shelf; a transverse guide member mounted on said apron, a carriage slidably 30 mounted on said guide member and ice tray release mechanism carried by said carriage. 35

DISCLAIMER

2,110,635.—*Homer E. Rosebrook and Othel I. De Graw, Greenville, Mich. REFRIGERATING APPARATUS.* Patent dated March 8, 1938. Disclaimer filed August 31, 1940, by the assignee, *Gibson Electric Refrigerator Corporation*.

Hereby enters this disclaimer to claims 2 and 3 of said patent.
[Official Gazette September 24, 1940.]

12. When the plate is up, the trays can be slid out from the shelf under the plate. To permit such swinging of the plate, its ends are provided with curved slots 33 and 33a as shown in Fig. 4, 5 engaging the pins 34 and 34a respectively. This construction permits the plate 32 to be rotated substantially 90° so that it can be moved from the position shown in solid lines to that shown in broken lines. The plate 32 is also removable 10 from the box. It is short enough so that it can be pushed to one side against the tension of one of the springs 35 until the pins from the other ends are released from the slots when the plate can be taken out bodily.

15. As another feature of the invention we have also shown the mounting of the thermostat 51a on the back of the apron 21, said thermostat being controlled by the usual knob 51 in co-operation with the dial 50. The wires 52 indicate 20 the usual connections of the thermostat to the rest of the refrigerating apparatus, the details of which need not be shown.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as permissible, in view of the prior art.

What we claim as new, and desire to secure by Letters Patent, is:

1. In refrigerating apparatus, in combination with a shelf type evaporator adapted to support ice trays thereon, a transverse guide member adjacent the front edge of the shelf, a carriage slidably mounted on said guide member, and an ice tray release mechanism carried by said carriage. 5

2. In refrigerating apparatus, in combination with a shelf type evaporator adapted to support ice trays thereon, a vertical plate mounted above 10 and in front of the shelf in front of the ice trays, and means for swinging said plate upwardly and backwardly to a horizontal position to permit removal of ice trays from said shelf and under said plate. 15

3. Apparatus as claimed in claim 2 in which the plate is bodily removable from the refrigerating apparatus.

4. Refrigerating apparatus, including: a shelf type evaporator; a transverse apron adjacent the 20 front edge of the shelf, the ends of said apron being bent backwardly at right angles; a transverse guide member carried by said backwardly bent ends of the apron, a carriage slidably mounted on said guide member; and ice tray 25 release mechanism carried by said carriage.

5. Refrigerating apparatus, including: a shelf type evaporator; a transverse apron adjacent the front edge of the shelf; a transverse guide member mounted on said apron, a carriage slidably 30 mounted on said guide member and ice tray release mechanism carried by said carriage.
